US0D1016851S

(12) United States Design Patent (10) Patent No.: US D1,016,851 S
Lo (45) Date of Patent: * Mar. 5, 2024

(54) DISPLAY SCREEN OR PORTION THEREOF
WITH GRAPHICAL USER INTERFACE

(71) Applicant: Canva Pty Ltd, Surry Hills (AU)

(72) Inventor: Gloria Lo, Bexley (AU)

(73) Assignee: Canva Pty Ltd, Surry Hills (AU)

() Term: 15 Years

(21) Appl. No.: 29/830,393

(22) Filed: Mar. 11, 2022

(30) Foreign Application Priority Data

Sep. 14, 2021 (AU) 202115554
Nov. 18, 2021 (AU) 202117169

(51) LOC (14) Cl. 14-04

(52) U.S. Cl.

USPC D14/489; D14/491; D14/492

(58) Field of Classification Search

USPC D14/485-495

(57) CLAIM

The ornamental design for a display screen or portion thereof with graphical user interface, as shown and described.

DESCRIPTION

The sole FIGURE is a front view of a display screen or portion thereof with graphical user interface showing my new design.

The dashed-dotted broken line in the FIGURE depicts a boundary line of a display screen or portion thereof, and forms no part of the claimed design.

1 Claim, 1 Drawing Sheet
